ACCUMULATOR COMPANY, OF PHILADELPHIA, PENNSYLVANIA, A CORPORATION
OF NEW JERSEY.

MARINE LANTERN.

1,170,086.

Specification of Letters Patent. Patented Feb. 1, 1916.

Application filed July 3, 1915. Serial No. 37,880.

To all whom it may concern:

Be it known that I, ELOF H. MEDÉN, a subject of the King of Sweden, residing in the city of Philadelphia, county of Philadelphia, State of Pennsylvania, have invented certain new and useful Improvements in Marine Lanterns, of which the following is a specification.

One of the objects of my invention is to provide a lantern with novel means for insulating or separating the fresh cool air entering the lantern from the gases of combustion and other heated gases which are escaping from the lantern so that a maximum difference of temperature between the two, which is essential to the proper function of the lantern, may be maintained.

A further object of my invention is to provide an opening for the escape of air or water which may find its way into the interior of the lantern with novel means for preventing the water from entering through said opening into the interior of the lantern, and also for preventing a strong or undue draft of air from blowing through said opening into or through said lantern.

A still further object of my invention is to provide novel means whereby access to the lamp or light flashing apparatus within the lantern may be facilitated and whereby also the interior of the lantern may be made more readily accessible for the purpose of being cleaned.

Other objects and advantages of my invention will be referred to in the detailed description thereof which follows or will be apparent therefrom.

In order that my invention may be more readily and clearly understood reference should be had to the accompanying drawings forming a part of this specification and in which,

Figure 1 is a central longitudinal sectional view of a lantern embodying my invention; and Fig. 2 is a transverse section thereof on the line 2-2 of Fig. 1.

Referring to the drawings, 1 designates the base of a lantern provided with projections 2 (one of which is shown) by means of which it may be secured to any suitable support. The flash light apparatus 3 or other suitable lighting means is supported upon the base 1 interiorly of the lantern. The lantern lens 4 is supported upon an inwardly extending lateral flange 5 which is

provided at the upper edge of an annular member 6 which is adapted to overlap, as indicated at 7, the upper edge of the base part 1. The annular member 6 is hingedly connected at 8 to the base 1 and is adapted to be held in closed position as shown in Fig. 1 by means of the screw-threaded headed bolt 10. Interposed between the flange 5 and the lower end of the lens 4 is a washer 11. A packing 12 is interposed between the outer lower edge portion of the said lens and the inner upper edge portion above the flange 5 of the annular member 6.

15 designates a tubular transparent member which may be designated as a chimney which surrounds and protects the light of the lighting apparatus 3. The said chimney is supported upon supporting brackets 16 (one only of which is shown) which are secured to the under side of projections 17 extending inwardly from the flange 5. In addition to the top of the lantern comprising the spaced cap-like portions 20 and 21 the hood of the lantern comprises a truncated cone-shaped member 22 and a corresponding member 23 spaced therefrom.

The member 22 is secured at its upper end to the upper end of the conduit 24 which conveys hot combustion and other gases from the interior of the lantern. The gases escaping from the conduit 24 pass over the upper edge of the same, through perforations in the skirt of the member 20, then over the upper edge of the member 22 and out under the lower edge of the member 21. Said member 22 is secured at its lower edge by means of rivets 25 to the upper part of the outwardly and downwardly inclined skirt-like portion 26 of the annular outwardly and upwardly flared member 27. The latter member extends around and is secured to the upper end portion of the annular member 30 which may be described generally as of inverted truncated cone-shape. In fact the two members 27 and 30 taken together may be so described. The lower edge of the said member 30 is in contact with and extends around the conduit 24 situated centrally of the upper portion of the lantern. The conduit 24 is provided with a bead 32 formed by pressing a ring of the metal thereof outwardly against which the lower edge of the member 30 contacts. The joint between the lower end of the member 30 and the conduit 24; also

- the connection between the lower end portion of the member 22 and the depending skirt part 26; and also the connection between the upper end of the said member 22 and the upper end of the conduit should be air-tight or nearly so so that the entry of air or gases into the space between the members 22, 27, 30 and 24 is prevented.
- It will be observed that the lower edge of the member 21 while it is spaced from the upper edge of the member 23 overlaps and extends below it and thereby tends to prevent the passage of water over the upper edge of the said member 23; also that the member 23 is provided with a baffle plate or flange 31 which tends to prevent the entry of water through the space between the lower edge portion of the member 21 and the upper edge portion of the member 23.
- For the purpose of preventing as far as possible the passage of water through the openings 35 (provided for the entry of fresh cool air into the interior of the lantern) and upwardly through the annular space between the members 22 and 23 the lower end of the member 22 is extended beyond its line of connection with the skirt 26 as shown at 36 and is bent or flared outwardly transversely of the said space.
- For the further purpose of preventing any water which may enter the openings 35 from passing into the interior of the lantern I have provided the annular member 40, the outer edge of which extends around and is seated against a depending flange 41 upon a flange 42 which extends laterally from the annular member 30. The said annular member 40 is inclined inwardly and upwardly and its upper end portion is bent or flared outwardly and is extended downwardly as indicated at 43 so as to form a baffle to prevent, as far as possible, the passage of water, which may travel underneath the lower edge of the skirt 26, into the interior of the lantern. The lower edge of the skirt 26 is situated relatively near to the inwardly and upwardly inclined portion of the annular member 40.
- The lower portion of the member 23 extends around and in contact with the lower end of the annular member 40 and its lower edge is bent inwardly around the lower edge of the flange 41 and is embedded in an annular ring of packing material 50 which extends around the upper end portion of the lens 4 and lies between the same and the flange 41 and in contact with the underneath side of the flange 42. The flange 42 is provided with a series of openings 51 (one only of which is shown) through which air which enters the openings 35 may pass into the interior of the lantern underneath the annular member 30. The provision for the passage of air into the interior of the lantern is necessary for the

purpose of supplying the oxygen essential for the combustion of the light flame. The openings 51 are partially closed by means of perforated members 55. The annular member 30 is supported by means of inclined braces or supports 56, the lower ends of which are secured to the projections 17 by means of screw-threaded bolts 57 which bolts also secure the brackets 16 in position.

Any water which may find its way into the interior of the lantern flows to the lower end thereof on to the bottom of the base 1, and escapes through an opening 60. In order to prevent the entry of water through said opening into the said lantern and also for preventing strong or undue drafts of air from blowing therethrough into the said lantern I have provided a depending flange-like portion 61 the lower end of which is extended inwardly as indicated at 62. The upper side of the said inwardly extended portion is beveled downwardly, as indicated at 63. I have also provided the said opening with a baffle construction which consists of annular plate-like members 65 which are supported at their outer edges, one upon the other, upon a shoulder 66 formed in the bottom of the base 1, which members extend inwardly and downwardly within the said opening 60. These annular members 65 are secured in position by means of screws 67 which extend through their outer edges and engage tapped openings in said shoulder. These screws also extend through the outer edge of and secure in position a spider-like member 68 which rests upon the uppermost of the annular members 65.

73 designates thin annular and downwardly extending members which alternate with the inner edges of the annular members 65. These annular members 73 are spaced from each other by means of sleeves 75 which are supported upon a bolt 76 which binds the said annular members 73 together and also to the center of the spider-like member 68. It is apparent that for either water or air to enter the lantern through the opening 60 it would be necessary for the same to travel a zigzag course around the overlying and overlapping edges of the flange 62 and the annular members 65 and 73. The means just described for partially closing the opening 60 permits access of air to the interior of the lantern so as to efficiently ventilate the same but prevents the same from blowing through the said opening with sufficient force or with sufficient draft to cause the extinguishment of the light.

It is apparent that by reason of the presence of the annular triangular space between the members 22, 27, 30 and the tubular conduit 24 the cool or cold air from the outside is prevented from contacting with the said conduit to cool the same. By this arrangement

ment the temperature of the air as it travels toward the burner of the lamp or flash light apparatus 3 is maintained at the lowest possible temperature while the temperatures of the escaping gases of combustion and heated air are maintained at as high a temperature as possible under the conditions of operation. These relative conditions of temperature are essential requirements for insuring 5 strong and proper draft and circulation of air through the lantern. The space between the members 22 and 23 is open at both the upper and lower ends so as to equalize the wind pressure and thereby prevent a draft 10 into the lantern to extinguish the light.

It is also apparent that when the securing or fastening bolt 10 is removed all of the upper portion of the lantern, including the annular member 6 and all of the parts supported thereon and thereby, may be turned 20 upon the hinge 8 so as to completely expose the lighting apparatus 3 to thereby render the same easily accessible for the purpose of repair or for any other purpose. Such construction and arrangement also enables 25 ready and easy access to the interior of the lens whereby it may be easily and readily cleaned.

I claim:—

30 1. In a lantern, the combination of a conduit for conveying from the lantern the gases of combustion and heated air, a casing extending around said conduit and forming a substantially air-tight insulating space 35 surrounding the same, and a casing extending around the upper portion of the first-named casing and being spaced therefrom to form a chamber surrounding the said upper portion of the said first-named casing, said 40 chamber communicating at its upper and lower ends with the air.

2. A lantern comprising a conduit for conveying the gases of combustion and heated air from the lantern, a hood surrounding 45 the said conduit said hood having double walls the inner wall being spaced from the said conduit intermediate its upper and lower ends and having substantially air-tight connection with the said conduit adjacent to its upper and lower ends to form a substantially air-tight chamber surrounding said conduit and the outer wall of said hood being spaced from the inner wall thereof to form a space surrounding the said inner wall 55 such space having communication at its upper and lower ends with the air, and means for supporting the said hood together with the said conduit.

3. In a lantern, the combination of a conduit for conveying from the interior of the lantern gases of combustion and other gases, a hood surrounding the said conduit and contacting therewith adjacent to its upper and lower ends and being spaced therefrom 60 between the said points of contact, said hood

comprising a portion having double walls spaced from each other, the space between the said walls being open at the top and at the bottom and said hood being provided with means whereby cool air may be admitted to the interior of the said lantern without contacting with said conduit and means for supporting the said hood together with the said conduit. 70

4. A lantern comprising a conduit for 75 conveying combustion and other gases from its interior, a truncated cone-shaped member having connection with the said conduit at its upper end, said member flaring downwardly and away from the said conduit and surrounding the same, an inverted truncated cone-shaped member extending around and contacting with the said conduit adjacent to its lower end, and an intermediate annular member having connection at its lower end with the upper end of the said inverted truncated cone-shaped member and flaring upwardly and outwardly and being bent and extended downwardly, and the said outwardly and downwardly extended portion 80 having connection with the lower end of the said truncated cone-shaped member. 85

5. A lantern comprising a conduit for 90 conveying combustion and other gases from the interior thereof, a truncated cone-shaped member having connection with the said conduit adjacent its upper end, means surrounding and contacting with the said conduit adjacent to its lower end said means flaring upwardly and outwardly and having 95 connection with the lower end portion of the said truncated cone-shaped member to form therewith an annular space surrounding the said conduit, a truncated cone-shaped member surrounding and being spaced from 100 the first-named truncated cone-shaped member, the space between the said members being open at top and bottom, the outside member having openings to permit the entry of cool air into the interior of said lantern, means for preventing the passage of water through said openings into the interior of the said lantern, and means for supporting the several parts of the structure hereinbefore enumerated. 105

6. In a lantern the combination of a lighting device, a lens surrounding the said lighting device, a conduit for conveying combustion and other gases from the interior of said lantern, a hood surrounding the said conduit and comprising two truncated cone-shaped members surrounding a portion of the said conduit one of the said members having connection with the said conduit at its upper end and the other one of said members having openings adjacent to its lower end to permit cool air to enter into the interior of the said lantern, and means having contact at its lower end with the said conduit adjacent to the lower end of the latter and be- 110 115 120 125 130

ing flared upwardly and outwardly and having connection with the inner one of the said truncated cone-shaped members and the said means having a flange resting upon the upper end of the said lens and means for supporting the said first-named means together with the said conduit and the said truncated cone-shaped members.

7. A lantern comprising a base having an opening in the bottom thereof to permit water which may enter the interior of the lantern to drain therefrom said opening having means to prevent the passage of water therethrough into the said lantern and also to prevent undue drafts of air from blowing into said lantern, said means consisting of a plurality of annular plate-like members one series of which is supported centrally of the said opening and the other series of which is supported at the edge of the said opening, the inner edges of the latter alternating with and being overlapped by the outer edges of the former.

8. A lantern comprising an opening through a wall thereof to permit any water which may enter the interior of the lantern to drain therefrom, said opening being provided with means for preventing the entry of water into the said lantern and also for preventing undue drafts of air from blowing into said lantern, said means comprising a plurality of downwardly and outwardly extended annular plate-like members supported centrally of the said opening and a plurality of downwardly and inwardly

extended annular plate-like members supported at the edge of said opening the inner edges of the last-mentioned plate-like members alternating with and overlapping and being overlapped by the outer edges of the first-named plate-like members.

9. A lantern having an opening through a wall thereof to permit water which may enter the interior of the lantern to drain therefrom said opening being provided with means for preventing the entry of water therethrough into the said lantern and also for preventing undue drafts of air from blowing into said lantern, said means comprising a flange which extends outwardly from the said wall which flange is provided with an inwardly extending portion, a plurality of annular plates spaced from each other and supported centrally of the said opening the outermost of the said plates being spaced from and overlying the inwardly extended portion of the said flange and a plurality of annular plates supported at their outer edges and extending inwardly to points intermediate the first-named annular plates and overlapping and being overlapped thereby, substantially as and for the purpose described.

In testimony that I claim the foregoing as my invention I have hereunto signed my name this 1st day of July, A. D. 1915.
